UNITED STATES PATENT OFFICE.

JAMES MONTGOMERY, OF SCOTTDALE, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

FLASK-CENTERING DEVICE FOR HELICAL RAMMING MACHINES.

Application filed July 9, 1921. Serial No. 483,416.

To all whom it may concern:

Be it known that I, JAMES MONTGOMERY, a citizen of the United States of America, and resident of Scottdale, in the county of 5 Westmoreland, in the State of Pennsylvania, have invented a certain new and useful Improvement in Flask-Centering Devices for Helical Ramming Machines, of which the following is a true and exact description, reference being had to the accompanying drawings, which form a part thereof.

My invention relates to helical ramming machines such as are used in making pipe 15 molds.

In machines of this class a series of flasks are supported and carried by a turntable into registry with a depending guide arm which supports the helical rammer, the 20 rammer being lowered into the flask and sand fed in between the flask and pattern and compacted by the helical rammer which rotates, tamping down the sand under its helical end surface and rising in the flask 25 as sand is fed in. Owing to the helical form of the sand compacting device considerable side thrust is exerted with a tendency to bring the flask out of proper alignment with the rammer and the object of 30 my invention is to provide such a machine with mechanism whereby the top of the flask in which the sand is being compacted shall be gripped to and held in proper registry with the frame supporting the ram- 35 ming mechanism so as to afford sufficient resistance to the side thrusts and maintain the parts in proper alignment.

The nature of my improvement will be best understood as described in connection 40 with the drawings in which it is illustrated in what I believe to be its best and most effective form and in which

Figure 1 is a view showing a portion of the top of the turntable with a flask supported thereon in the usual manner, said view showing also a portion of the usual framing for supporting ramming mechanism and showing in connection therewith my improved flask gripping mechanism.

Figure 2 is a front view of the mechanism shown in Fig. 1 with gripping mechanism in operative position shown in full lines and in retracted position shown in dotted lines.

Figure 3 is a view of driving mechanism used for rotating the helical rammers. 55

Figure 4 is a sectional view of the head and one of the helical rammers showing how it is engaged by the rotating mechanism, and

Figure 5 is a cross sectional view on the 60 line 5-5 of Fig. 4.

A is the top of a rotating turntable having a peripheral upwardly extending flange as indicated at A'. B indicates one of the flasks, as illustrated, a double flask supported on the flange A' of the turntable by a lug indicated at C. B' indicates the top of the flask. D indicates a framing supported above the turntable, D' indicating the top of this framing. D² and D³, usual 70 parts of the truss of which the framing is made up. E, E, are angle irons supported on the frame D and making up with proper connecting braces a supporting frame and guideway for the helical frame and rammers. F, F, are iron plates secured to the angles E and to the members D³, as shown, and F' a plate extending between and secured to these plates F, secured on the top D' of the framing. G is the driving mechanism for giving rotary motion to the helical rammers, as shown, see Fig. 3. The rotating shaft G communicates this motion through the bevels G' and G² to the shaft G³ which through a pinion G⁴ and a pinion 85 G⁵ communicates motion to the shaft G⁶ which in turn through the bevels G⁷, G⁸, G⁹ and G¹⁰ gives rotary motion to the vertical shafts H, H', the lower portions of which are squared. I, I', Fig. 3, indicate pulleys over 90 which extend cords, not shown, which may be attached to the tops of the helical rammers and to which in turn may be attached counterweights for balancing such portion of the weight as may be desirable. J and 95 J' are the heads of the helical rammers, the construction of which is best shown in Figs. 4 and 5. These heads are made up of portions J² having squared openings J³ in their tops through which extends the squared 100 shafts H or H'. The portions J² are formed in the thimbles J⁴ and on these thimbles fits a nut J⁵ between which and the enlarged portion J² is held a ring K having outwardly extending arms K' with forked 105 ends K² which engage on flanges of the angle

irons E as indicated in Fig. 5. L, L' and L² and L³ are antifriction rollers held in the portion J² and in engagement with squared shaft H.

5 Secured to the thimbles J⁵ are the depending cylinders Q, Q', to the lower ends of which are secured the helical rammers indicated at Q². M, M, Figs. 1 and 2, indicate pulleys over which extend cables M' connected with counterbalancing weights not shown and with a portion of the gripping mechanism to be described.

N, N, are slotted guide plates secured to the bottom of the framing E as indicated in 15 Figs. 1 and 2. O, O, are rock shafts secured in bearings on the plates F, F, and having in a convenient place for the operator actuating levers O'. To these rock shafts are also secured levers O², O², which 20 are pivotally connected at their ends with gripping jaws P, P, the lower ends of which pass through the guides N, N, as shown. The ends of the levers O² are connected with the cables M' so that the action 25 of these cables tends to throw the levers up to the positions shown in dotted lines in Fig. 2.

The size and proportions of the levers O², the gripping jaws P and the guides N are 30 such that when the gripping jaws are forced downward their ends P' will grip and hold the top B' of the flask, as shown in Fig. 2, while when elevated these jaws will take the position shown in dotted lines in Fig. 2.

35 In operation the turntable is rotated to bring a flask into registry with the helical rammer or rammers which, of course, are in their retracted or uppermost positions as indicated in Figs. 1 and 2. The operator then seizes the levers O' which are normally in the position shown in dotted lines in Fig. 2 and moves them downward and toward each other to the position shown in full lines in Fig. 2. This motion of the 40 levers rotates the rock shaft O and the levers O² which in turn communicates motion to the jaws P, P, forcing their upper ends outward and their lower ends inward as these jaws move down until the ends P' P' of the 45 jaws engage and clamp the top of the flask as shown in Fig. 2, gripping the top of the flask firmly to the frame and insuring proper alignment of the flask during the ramming 50 operation. The operator then lowers the

helical rammer into the flask, feeding molding sand into the top of the flask and the rotation of the helical rammer rams and packs sand into the flask, raising, of course, when the flask is filled with sand until the mold is completed after which the rammers 60 are raised to clear the top of the flask, the gripping jaws are retracted and a new flask brought to registry with the frame and rammers.

Having now described my invention, what 65 I claim as new and desire to secure by Letters Patent, is:

1. In a helical pipe mold ramming machine comprising a turntable for supporting and moving the flasks and a depending frame for guiding the helical rammer, means supported on the lower part of said frame for gripping and holding a flask to the depending frame and in proper registry with the rammer. 75

2. In a helical pipe mold ramming machine comprising a turntable for supporting and moving the flasks and a depending frame for guiding the helical rammer, means supported on said frame for gripping and holding a flask in proper registry with the rammer, said means consisting of gripping jaws normally held retracted and extended on the frame and means for moving the jaws downward and together to grip the flask. 80

3. In a helical pipe mold ramming machine comprising a turntable for supporting and moving the flasks and a depending frame for guiding a flask gripping device consisting of guides secured to the bottom of the frame, gripping jaws the lower portions of which extend through said guides and means secured to the upper ends of the jaws for moving them down and up to grip and release the top of a flask. 90

4. In a helical pipe mold ramming machine comprising a turntable for supporting and moving the flasks and a depending frame for guiding a flask gripping device consisting of guides secured to the bottom of the frame, gripping jaws the lower portions of which extend through said guides, rock shafts having lever arms secured to the tops of the jaws whereby said jaws are moved down and up to grip and release the top 100 of a flask and lever arms secured to the rock shafts for operating them. 105

JAMES MONTGOMERY.
